SERIES LAMP CUTOUT

Frank W. Godsey, Jr., Pittsburgh, Pa., assignor
to Westinghouse Electric Corporation, East
Pittsburgh, Pa., a corporation of Pennsylvania

Application March 28, 1950, Serial No. 152,419

8 Claims. (Cl. 200—118)

1

My invention relates, generally, to switch devices, and more particularly to cutout devices for series lighting circuits and the like which function in response to the failure of the lamp to short-circuit the lamp terminals and provide a continuation of the series circuit.

The object of my invention, generally stated, is to provide an improved cutout device for series lighting circuits and the like which shall be simple, reliable and compact construction, and which may be economically manufactured and used.

A more specific object of my invention is to provide a cutout device embodying a thermally controlled or released mechanical switch element.

Another object of my invention is to provide a cutout device wherein the short-circuiting or circuit-closing operation is performed by a resilient or flexible contact element which is released from a normally open position to a contact making position in response to a predetermined increase in the temperature of the device resulting from increased voltage applied thereto due to lamp failure.

A further object of my invention is to provide a cutout device of the character described wherein the shunting or circuit making operation is effected by a flexible contact spring normally retained in an open position by a quantity of solder which is melted to release the contact spring in response to an increase in the operating temperature of the device due to the interruption of the series circuit through the lamp.

A still further object of my invention is to provide a cutout device of the character described wherein the contact spring is normally held in an open or retracted position by a thermally responsive latch member or device which is actuated in response to a predetermined increase in temperature to release the contact spring.

Another object of my invention is to provide a cutout device of the character described wherein the necessary heat to trip or release the contact spring is produced in the device itself by passing current through a small block or ring of non-linear conducting material.

It is also an object of my invention to provide a cutout device of this kind which may be reset or readjusted to its normal operating condition after it has once operated to short-circuit the lamp.

These and other objects of my invention will be more readily understood from the following detailed description, when considered in conjunction with the drawing, in which:

2

Figure 1 is an elevational view, in section, of a cutout device embodying the principal features of my invention;

Fig. 2 is a sectional view taken along lines II—II of Fig. 1;

Fig. 3 is an elevational view, in section, of a modification of my invention; and

Fig. 4 is a sectional view taken along lines IV—IV of Fig. 3.

10 In practicing my invention in its preferred form, the cutout device is formed in the usual button or wafer shape and comprises a spacer element in the form of a block, a pair of blocks, or a ring of fused silicon carbide clay pressed or held between two metal discs constituting the contact plates or terminals of the device. The spacer, in whatever form it may take, is of such nature that a recess or cavity is formed in the device in which the switch or contact making element is positioned. In one form of my invention, a spring contact member is rigidly attached at one of its ends to the interior surface of the upper plate, and its opposite free end is normally biased by spring action to engage the other or lower plate. The free end of the contact spring is normally held out of engagement with the lower plate by soldering it to the inner surface of the upper plate. The current flowing through the spacer element in response to lamp failure 15 results in the development of a sufficient amount of heat to melt the solder and thus release the contact spring to a circuit making position. In a modification of my invention, the contact spring is held out of contact making engagement 20 with the lower contact plate by a small bimetallic latch member which likewise functions to release the contact spring as a result of heat developed in the spacer element as before.

25 Referring now to Figs. 1 and 2 which show the preferred embodiment of my invention, it will be observed that one contact plate 10, which may be termed the upper plate, is in the form of a solid flat disc, and the other contact plate, which may be termed the lower plate, is in the form of a flat bottomed cup 11 having a bottom portion 12, and an upright or side portion 13.

30 As shown in Fig. 2, the spacer element for the contact plates is formed in two parts or blocks 15 and 16 spaced apart to provide a central elongated cavity 17. These spacer blocks fit 35 within the cup 11, resting directly upon the bottom portion 12 of the cup, which in this instance is the lower contact plate, and are tightly held therein by the upper plate 10 which 40 may be secured in any suitable manner, such as

by crimping or otherwise forming the upper edge 18 of the side of the cup 11 as shown in Fig. 1.

The plates 10 and 12 may be insulated from each other by suitable insulating material 21, such as fish paper, which is placed within the cup 11 around the spacer blocks and bent over under the crimped portion as shown in Fig. 1. It will be understood that this insulates the contact plates from one another so that when a voltage is impressed across the device, that is across the plates 10 and 12, the current must flow through the spacer blocks 15 and 16.

The plates 10 and 12 may be formed of any suitable material, such as copper, brass, etc., which is easily worked or formed and which has good electrical qualities.

The spacer blocks 15 and 16 may be formed of non-linear conducting materials such as copper-oxide films, aluminum-oxide films, crystal aggregates, etc. It is preferred, however, to use a material such as fused silicon carbide clay. This material is of a ceramic nature and as formed by mixing silicon carbide crystals with ball clay, milling and packing at a high temperature. The surfaces of the blocks are made conducting by spraying or otherwise applying a suitable metallic coating.

This preferred material has a non-linear conduction characteristic which provides for greatly increased current flow as the voltage increases. As an example, the current might be 5 milliamperes at 50 volts, 20 milliamperes at 57 volts, and 3 amperes at 200 volts, depending upon the exact characteristic of the material which may be varied over an appreciable range of manufacture.

The switch or contact making element of the device is in the form of a flat leaf spring 22 of Phosphor bronze, or the like, having one end 23 rigidly attached to the interior surface of the upper plate 10 by means of a rivet 24 or otherwise, and its other or free end 25 attached to this same contact plate by means of a small quantity of 50-50 solder or the like as indicated at 26 in Fig. 1. It will be understood that the contact spring 22 is to be held in a substantially flat position against the bottom surface of the upper contact plate 10 with its free end 25 out of engagement with the bottom plate 12. The spring is so shaped or biased that when it is released by the melting of the solder, the free end 25 will snap into engagement with the contact plate 12 and thus provide the necessary short-circuiting connection for the lamp.

As shown best in Fig. 2, the contact spring 22 is positioned within the cavity or channel 17 formed by the two spacer blocks 15 and 16. The contact spring is thus completely enclosed within the casing formed by the cup 11 and the upper contact plate 10.

If desired, the lower contact plate 12 may be provided with a small opening 27 directly beneath the free end 25 of the contact spring so that a suitable instrument may be inserted to push the freed end of the contact spring back to its normal position once it has been released. This makes it possible to reset the cutout device to its normal operating condition by applying sufficient heat by means of a soldering iron to the upper plate 10 to remelt the solder 26 and thus again detachably secure the free end 25 of the contact spring to the upper plate.

Referring now to Figs. 3 and 4 which show a modification of my invention, it will be observed that in this instance the lower contact plate 31

is in the form of a flat disc and the upper contact plate 32 is formed as a shallow cup-shaped element of the same general shape, but having a circular indentation 33 which is clearly shown in Fig. 3.

In this instance the spacer element is in the form of a ring 34 and is comprised of the same material as the spacer blocks 15 and 16 of the preferred embodiment. The contact plates 31 and 32 may be securely held in position on opposite sides of the spacer ring 34 in any suitable manner.

In this embodiment the contact spring 35 is mechanically controlled or released by means of a small mechanical latch 36 which may be formed of bimetal. As shown best in Fig. 3, the contact spring 35 is rigidly attached by means of a rivet 37, or otherwise, to the upper surface of the contact plate 32, and is provided at its free end 38 with a contact 39 extending through a small opening 41 in the contact plate. This contact spring is normally shaped or biased so that it moves down and causes the contact element 39 to engage the lower plate 31.

The thermally responsive latch member 36 is shown best in Fig. 4. It may be L-shaped and attached at one end 42 to the contact plate 32, and so positioned with respect to the contact spring 35 that its end portion 43 normally engages the contact spring and holds it in a raised position with the contact member 39 out of engagement with the lower plate 31. Any other suitable arrangement or shape of latch may be used.

It will be understood that, in this instance, when the device is subjected to more than its normal operating voltage, the heat generated by current flowing through the spacer ring 34 will cause the latch 36 to release the contact spring 35.

The device may be reset for further operation by simply raising the contact spring and re-engaging the end of the latch member 36 therewith.

In view of the foregoing detailed description of the two embodiments of my invention, it will be apparent that I have provided a new type of series cutout device which is in the form of a positive acting switch mechanism. The device, in either of its two forms, is of a simple nature and is economical to manufacture and use. It is a positive acting device which may be used over and over again due to the resetting feature of the contact elements.

While I have described and shown specific embodiments of my invention, it will be apparent that changes and alterations may be made therein without departing from the principles of the invention. The devices disclosed are merely illustrative of the several different forms my invention may take.

I claim as my invention:

1. An electric cutout device comprising, two conducting surfaces, spacer means disposed in contact relation therebetween, said spacer means being formed of a non-linear conducting material, a movable contact member mounted on one of said surfaces, a thermally responsive means normally retaining said contact member in an open position, and operable to connect said surfaces together when heated to a predetermined degree by current flow through said spacer means.

2. An electric cutout device comprising, two conducting surfaces, spacer means disposed therebetween, said spacer means being formed of

a non-linear conducting material and so shaped as to provide an elongated inner cavity, a movable contact member mounted in said cavity operable when in its closed position to connect said surfaces, and thermally responsive means normally retaining said contact member in an open position and operable to release said contact member to its closed position.

3. An electric cutout device for series lighting circuits and the like comprising, a pair of spaced contact plates of conducting material, a pair of spacer blocks disposed therebetween and in intimate contact therewith, said blocks being formed of a non-linear conducting material and being spaced apart to provide an elongated channel between the plates, and a contact spring mounted in said channel with one end rigidly secured to one plate and its opposite end soldered to the same plate, whereby said other end is releasable by the melting of the solder and operable to engage the other plate.

4. An electric cutout device for series lighting circuits and the like comprising, a pair of spaced contact plates of conducting material, a spacer ring of non-linear conducting material disposed therebetween, a movable contact element attached to one of said plates and biased into engagement with the other plate, and a thermally responsive latch attached to said one plate for normally retaining said contact element out of engagement with said other plate.

5. A cutout device for series lighting circuits and the like comprising, a cup-shaped member of conducting material having a flat bottom portion, a pair of spacer blocks of non-linear conducting material disposed in said member, said spacer blocks being spaced apart to provide an elongated channel, a flat disc-shaped member of conducting material disposed in the cup-shaped member over the spacer blocks with the upper edge of the cup-shaped member crimped over upon the disc to retain it in position, insulation disposed between said cup-shaped member and the disc, and a thermally responsive contact member disposed in said channel normally engaging the disc-shaped member and operable in response to a predetermined rise in temperature resulting from the passage of electric current through the spacer blocks to also engage the bottom of the cup-shaped member.

6. A cutout device for series lighting circuits and the like comprising, a pair of conducting members, spacer means interposed therebetween and in intimate contact therewith, said spacer means being formed of a fused silicon carbide clay having non-linear conducting characteristics, a movable contact member mounted on one

of said surfaces and thermally responsive means normally retaining said contact member in an open position, and releasing said movable contact member to engage both surfaces in response to the development of a predetermined amount of heat in the spacer means as the result of current flow therethrough.

7. A cutout device for series lighting circuits and the like comprising, a pair of metallic plates, a pair of spacer blocks interposed therebetween and held in intimate contact relation therewith, said spacer blocks being so positioned relative to each other as to form a cavity between the plates and being formed of a fused silicon carbide clay, a contact spring rigidly attached at one end to one of said plates within the cavity and biased to engage the other plate with its free end, and thermally responsive means mounted on said one plate functioning to normally hold said free end of the contact spring out of engagement with said other plate.

8. In an electric cutout device for series lighting circuits and the like comprising, a pair of spaced contact plates, a spacer ring of fused silicon carbide clay interposed therebetween, one of said plates being substantially flat and the other being shallow cup-shaped with a flat bottom portion extending downwardly within the ring and having an opening therein adjacent one side, a contact spring mounted within the cavity formed by the cupped plate with one end rigidly secured thereto and the other end carrying a contact member extending through said opening in the bottom of the cupped plate, said contact spring being normally biased to cause said contact member to engage the flat plate, and a bimetallic latch member mounted on the cup-shaped plate normally functioning to hold the contact-spring in a retracted position and operable in response to predetermined temperature conditions of the cutout to release the contact spring.
